(57) **CLAIM**

The ornamental design for a fortune telling device, as shown and described.

DESCRIPTION

FIG. 1 is a perspective view of a fortune telling device, the broken lines which show a holder, are for illustrative purposes only and form no part of the claimed design; FIG. 2 is a front elevational view thereof, the rear elevational view not being shown as it would be a mirror image of the front elevational view;

FIG. 3 is a bottom elevational view thereof;

FIG. 4 is a right side elevational view thereof, the left side elevational view not being as it would be a mirror image of the right side elevational view;

FIG. 5. is a front elevational view of a folded paper and string, which are part of the fortune telling device, shown broken away for ease of illustration;

FIG. 6 is a right elevational view thereof;

FIG. 7 is a left elevational view thereof;

FIG. 8 is a rear elevational view thereof;

FIG. 9 is a top elevational view thereof;

FIG. 10 is a bottom elevational view thereof;

FIG. 11 is an exploded perspective view thereof;

FIG. 12 is a sectional view of a fortune telling device, the broken lines showing a holder; and,

FIG. 13 is a perspective view showing a partially folded paper and a string.
